UNITED STATES PATENT OFFICE

149,236

DESIGN FOR A WINTER SPORT SHOE

Floyd C. Treat, Barrington, Ill., assignor to Athletic Shoe Company, Chicago, Ill., a corporation of Illinois

Application September 27, 1947, Serial No. 141,598

Term of patent 14 years

(Cl. D7—7)

To all whom it may concern:

Be it known that I, Floyd C. Treat, a citizen of the United States, residing at Barrington, in the county of Lake and State of Illinois, have invented a new, original, and ornamental Design for a Winter Sport Shoe, of which the following is a specification, reference being had to the accompanying drawing, forming a part thereof, in which:

Fig. 1 is a view in perspective of a shoe showing my new design.

Fig. 2 is a view of the shoe in front elevation in partially closed position.

I claim:

The ornamental design for a winter sport shoe, substantially as shown.

FLOYD C. TREAT.
